UNITED STATES PATENT OFFICE.

JONAS NORTHROP, OF HOPEDALE, MASSACHUSETTS, ASSIGNOR TO DRAPER COMPANY, OF HOPEDALE, MASSACHUSETTS, A CORPORATION OF MAINE.

THREAD-PARTING MECHANISM FOR LOOMS.

No. 866,052.

Specification of Letters Patent.

Patented Sept. 17, 1907.

Application filed January 16, 1907. Serial No. 362,480.

To all whom it may concern:

Be it known that I, JONAS NORTHROP, a citizen of the United States, and a resident of Hopedale, county of Worcester, State of Massachusetts, have invented 55
5 an Improvement in Thread-Parting Mechanism for Looms, of which the following description, in connection with the accompanying drawing, is a specification, like letters on the drawing representing like parts.

This invention has for its object the production of 10 novel mechanism for parting the filling between the cloth and the shuttle, at the replenishing side of a loom provided with mechanism to automatically provide the running shuttle with a fresh supply of filling. Such a replenishing loom is, for example, shown in 15 United States Patent No. 529,940, granted to Northrop November 27, 1894, looms of this type being technically known as "Northrop" looms.

When a change of filling is effected the old filling end, (that is, the length of filling leading from the cloth 20 to the filling-supply in the shuttle and about to be abandoned,) must be severed and removed in order to prevent it from being carried back into the cloth, or from fouling the fresh filling inserted in the shuttle. Means have been provided heretofore to part such filling-end adjacent the cloth by means of a temple thread-cutter, and to part it near the shuttle by other means. 25

In my present invention I have provided means to part the old filling adjacent the cloth, causing the operation of such means positively and definitely at the 30 proper instant, instead of depending on the somewhat uncertain action of a temple thread-cutter. Herein such parting means is operated a second time to part the new filling-end which extends from the filling-feeder or hopper to the cloth after the first shot of the 35 replenished shuttle, after which second operation the parting means remains inoperative until the next filling-replenishment is called for. I have also provided novel means to part the old filling-end at the shuttle, and as will appear hereinafter such parting or severance takes place at a point nearly opposite the head of 40 the filling-carrier in the shuttle and about to be ejected. This insures a very short length of filling to be drawn out of the shuttle eye by the ejected filling-carrier, eliminating any fouling of the fresh filling simultaneously inserted in the shuttle.

The length of filling severed by the two parting means is, in the present embodiment of my invention engaged by a thread-catcher, conveniently mounted on the shuttle-feeler, the thread-catcher grasping the 50 severed piece of filling and drawing it forward out of the way as the part on which the catcher is mounted returns to normal position.

The opening and closing of the clamping members or jaws of the thread-catcher is effected automatically at the proper times. 55

The various novel features of my invention, one practical embodiment whereof is illustrated in the accompanying drawings, will be fully described in the subjoined specification and particularly pointed out in the following claims. 60

Figure 1 is a top plan view of a portion of the replenishing side of an automatic loom with one embodiment of my present invention applied thereto, the various parts being in normal position; Fig. 2 is a front elevation of the mechanism illustrated in Fig. 1, the outer 65 end of the filling-feeder being indicated by dotted lines; Fig. 3 is a partial right hand side elevation of the loom, but with the filling-feeder and the lay in transverse section, the section through the lay being taken near the inner end or mouth of the replenishing 70 shuttle-box; Fig. 4 is a detail of the thread-parting means which act upon the thread or filling adjacent the shuttle, in the position shown in Fig. 3 but with the bracket for the tip-support broken off; Fig. 5 is an enlarged inner side elevation of the lower end of the 75 blade-carrier and parting blades shown in Fig. 4; Fig. 6 is a view similar to Fig. 3, but showing the transerrer operating to insert a fresh supply of filling into the shuttle, while the parting blades have just been closed to part the old filling-end, the lay not having reached 80 front center to complete filling replenishment; Fig. 7 is an enlarged transverse sectional detail, on the line 7—7, Fig. 1, looking toward the right, showing the thread-catcher in normal position; Fig. 8 is an enlarged side elevation of the thread-catching jaws in closed position; 85 Fig. 9 is an opposite side view, also enlarged, of the thread-catcher, with the jaws open; Fig. 10 is a cross-section on the line 10—10, through the jaws, Fig. 8, looking toward the right; Fig. 11 is an enlarged detail in perspective of the end of the jaw opener, to be described; Fig. 12 is an inner side elevation of the thread-parting means adjacent the cloth, taken at the left of the line 7—7, Fig. 1, showing the temple and the contiguous filling-detecting mechanism, the thread-parting means being in normal condition; Fig. 13 is a similar view, to the left of the line 13—13, Fig. 1; Fig. 14 is a detail, partly in section on the line 14—14, Fig. 1, showing the parting blades or cutters in retracted or housed position, by full lines, and by dotted lines in position to operate. Fig. 15 is a similar view but showing the blades or cutters as having closed to part a filling-end, and in readiness to be retracted or restored to 90 normal position.

Referring to Figs. 1, 2, 3, 4 and 6, the filling-feeder F

to hold a plurality of filling-carriers or bobbins *b*, in reserve, the transerrer *f'* mounted to rock on the fixed stud *f*, to remove the filling-carriers one by one, and transfer them to the running shuttle *S*, Figs. 3 and 6, 5 (of the automatically self-threading type) the controlling rock-shaft *d'* having an attached arm *d*² normally held depressed as in Figs. 3 and 7 by a suitable spring *S*⁴, the lay *A*³ cut away at *A*¹⁰ below the replenishing shuttle-box *B*⁴, the latter being slotted in its bottom at 10, Figs. 3 and 6, to permit the discharge of a filling-carrier when ejected from the shuttle, by the incoming filling-carrier at the time of filling replenishment, are and may be all of well known construction and operation in the Northrop type of loom, hereinafter referred to.

The tip-support *f*² shown best in Fig. 3 is of usual construction and is pivotally mounted on the bracket *f*⁴ rigidly secured to the outer end of the stud *f*, and operates in usual manner.

20 In Figs. 4 and 6, I have omitted the tip-support and broken off the stand *f*⁴ in order to show more clearly the parts which would be otherwise hidden.

The notched dog *m*¹⁵ pivotally connected at 2 with the downturned bifurcated extension *f*³ of the transerrer, the bunter *C*² on the lay to coöperate with the dog when filling-replenishment is to be effected, the shuttle-feeler arm *y*⁴ fulcrumed on a short rocker-shaft *y* mounted on the loom-side, the shuttle-feeler arm having a lug *y'*, Fig. 7, with which coöperates the arm *d*², 30 and the arm *y*² having a cam-slot *y*³ to coöperate with the lug *m*¹⁴ on the dog *m*¹⁵ are all substantially as shown in United States patent to Stimpson No. 718587, dated January 13, 1903, the lower end of the arm *y*² being rigidly connected with the rocker-shaft *y* in any suitable manner.

In the present embodiment of my invention, the shuttle-feeler arm *y*⁴ not only is arranged to feel for and ascertain whether the shuttle is properly boxed in the box *B*⁴ when replenishment of filling is called for, but 40 it also carries a thread-catcher, to be hereinafter described. The function of the thread catcher is to engage and withdraw the length of thread or filling parted adjacent the cloth and the shuttle.

The pivot or fulcrum 2 is extended upwardly and 45 rearwardly at 3, and at its extremity outturned at 4, as best shown in Fig. 2, to positively insure the opening of the parting members or blades which form a part of the means for severing or parting the old filling-end at the shuttle.

50 An upturned arm 5 is rigidly bolted at its lower end at 6 to the inner face of the bracket *f*⁴, said arm having an inwardly and horizontally extended pin 7 at its upper end, on which is mounted an elongated sleeve-like hub 8, shown as a part of a casting constituting a blade-carrier, said casting comprising an elongated depending key 9, having a forwardly extended offset 10 to the apex of which at 11 is attached a spring 12, clearly shown in Fig. 4, the lower end of the spring being in turn secured to a lateral lug 13 on the transerrer, and 55 extended below the face 14 of the offset 10.

The blade-carrier is adapted to swing on the pivot or fulcrum pin 7, toward and from the lay, and when the transerrer is in normal or retracted position, see Figs. 3 and 4, the lug 13 acting upon the face 14 positively

moves the blade-carrier forward into inoperative position.

When the transerrer is operatively moved, to transfer a fresh supply of filling from the feeder to the shuttle, the yielding connection 12 between the transerrer and blade-carrier operates to swing the latter rearwardly 70 into operative position, shown in Fig. 6.

The blade-carrier swings in a path parallel to and near the path of movement of the transerrer, as will be manifest from an inspection of Figs. 1 and 2, and as the transerrer engages the head of the filling-carrier or bobbin to be transferred, it will be manifest that the blade-carrier will move toward or from the shuttle at a point near the head of the filling-carrier therein.

The lower end of the blade-carrier is rearwardly extended at 15, and is provided with a cutting blade 16, 80 see Fig. 5, to coöperate with a relatively movable blade 17 pivotally mounted on a stud 18 extended through the blade-carrier.

The stud is held from movement in the blade-carrier and at its inner end is enlarged to form a head 19, Fig. 85 5, and a barrel 20 around which is coiled a spring 21, one end of the spring being attached to the head 19 at 22, and the other end of the spring is held by a pin 23 on an enlargement 17⁴ of the blade. The spring not only serves to press the cutting edges of the blades 16 90 and 17 together, but also normally acts to hold the blades open, the movement of the blade 17 being limited by a pin 24 on the blade-carrier extended through a slot 25 in the enlargement 17⁴. The said enlargement is upturned at its front portion to present a cam-like 95 face 26, and at its rear portion the enlargement 17⁴ is upturned at 27, and provided with a lateral offset 28 extended above the toe 15 and across the rear face of the blade-carrier, as clearly shown in Figs. 3 and 4.

When the blade-carrier is returned to normal position, the bent end 4 of the pivot 2 engages the cam edge or face 26, and positively insures the opening of the blades as in Figs. 3 and 4, if for any reason the spring 21 should act too sluggishly.

The shuttle *S* is provided in its front wall with an 105 opening *s*⁴, Figs. 3 and 6, which opening may be the usual opening for the introduction of the feeler in a so-called "feeler" loom, the opening being near the head of the filling-carrier, and I have herein shown the front wall of the replenishing shuttle-box *B*⁴ as provided 110 with an opening *b*⁴, so located that when the shuttle is properly boxed for replenishment, the openings *s*⁴ and *b*⁴ will register.

The blades on the blade-carrier are arranged to move rearwardly into the aperture *b*⁴ when the blade-carrier 115 is operatively positioned, and the lay beats up, as shown in Fig. 6, it being understood that the blades will be open when they enter the aperture and they will remain open until they enter the opening *s*⁴ in the shuttle, receiving between them the old filling-end. 120

It will be understood of course that the old filling-end leads from the eye of the shuttle between the front wall of the latter, and the inner face of the box-wall, thence to the cloth at the-replenishing side of the loom, and when the blade-carrier is moved into operative position 125 by or through the actuation of the replenishing mechanism, the old filling-end must be brought between the edges of the blades.

To those skilled in the art, it will be plain that the lay must move forward from the position shown in Fig. 6, in order to complete the transfer of a filling-carrier from the feeder to the shuttle, a filling-carrier in process 5 of transfer being shown by dotted lines at b^6 just about to enter the shuttle, but before the lay quite reaches the position shown in Fig. 6, the overhanging flange 29 of the front wall of the shuttle-box will be brought into engagement with the lateral offset 28, and will 10 thereby turn the blade 17 on its pivot into the position shown in Fig. 6, to part the filling-end. As a matter of fact, the filling-end is parted before the transfer of filling is completed, but the completion of the forward movement of the lay will swing the blade-carrier 15 forward slightly, the spring or yielding connection 12 between said blade-carrier and the transerrer permitting such movement. As the lay goes back and the transerrer f' returns to normal position, the blade-carrier is returned to its normal, inoperative position, 20 and the end 4 of the rod 3 acts to insure the opening of the blades, as has been described. As the old filling-end is parted substantially opposite the head of the filling-carrier about to be ejected therefrom, it will be clear that a very short length of filling will remain to 25 be drawn out through the eye of the shuttle, as such ejected filling-carrier is discharged through the guide-way portion A^{10} of the lay, so that there is practically no chance for any fouling of the old filling with the fresh or incoming shuttle and absolutely no chance for 30 the old filling to be carried back into the cloth.

If the shuttle-feeler to be hereinafter referred to prevents the operation of the replenishing mechanism, the blade-carrier will not be moved into operative position.

35 The operative positioning of the means for parting the old filling-end at the shuttle is effected by or through the operation of the filling-replenishing mechanism, as has been described, and the actual closing of the parting members or blades to part the filling-end 40 is positively effected by or through the lay on its forward beat at the time of filling-replenishment.

It is necessary to part the filling-end adjacent the cloth at the replenishing side of the loom, and this has been accomplished heretofore by so-called temple 45 thread-cutters and by other devices more or less positive or definite in their action, but in actual practice these devices have at times failed to part the old filling end with the certainty and positiveness which is desirable, and at a definite time.

50 The parting means embodied in my present invention for parting the filling-end adjacent the cloth is controlled as to its operation by or through the actuation of the replenishing mechanism, and is actuated positively and at a definite time, and I have so arranged 55 the mechanism that it not only parts the old filling-end, but it also parts the new filling-end due to filling-replenishment.

Referring to Figs. 1, 12 and 13, I have shown a temple T of suitable construction, mounted on the breast-beam of the loom at the replenishing side thereof, the temple shank having the usual depending heel t to be engaged by the lay on the forward beat thereof, and the pod and cap of the temple are herein shown as shaped to form a box-like housing 30 having an elongated

slot 31 in its top, the housing having slidably mounted within it the rear end of a blade-carrier 32, see Figs. 14 and 15, to the extremity of which is rigidly attached an upper blade 33, a co-operating blade 34 being pivotally mounted on the blade-carrier at 35, and having an upturned lug 36, extended through the slot 31. A flat spring 37 on the blade-carrier presses at its free end upon the pivoted blade 34 and maintains it yieldingly against the co-operating blade 33, to insure proper cutting action. The blade-carrier is provided with a depending heel 38 and is also forwardly extended 75 to present a flattened and elongated extension 39 longitudinally slotted at 40 to receive a guide-lug 41 extended laterally from the temple stand T^X . The extension has an upturned shoulder or abutment 42, and a forwardly extended, rigid rod 43, slideable in a guide-ear 44 on the temple-stand. 80

Between the abutment or shoulder 42 and the guide-ear, a spring 44 X is coiled around the rod 43, to move the blade-carrier in the direction of the arrow 45, Figs. 12 and 13, when the spring is free to act. 85

When the blade-carrier is in its normal position, Figs. 12 and 13, and full lines Fig. 14, the two blades are retracted within the housing and are open, see Figs. 13 and 14, the opening of the blades being caused by engagement of the lug 36 with the front end of the slot 31 in the housing. 90

When the blade-carrier is moved rearwardly by the action of the spring 44 X , the blades will move out of the housing bodily and in their open position, see dotted lines Fig. 14, until the lug 36 strikes the rear end of the slot 31, whereupon the blade 34 will be swung upward on its pivot 35 into the closed position, see Fig. 15, and if the filling is caught between the open blades, such positive closing thereof will part the filling positively and effectually. If now the parts are in the 100 position shown in Fig. 15, and the lay beats up, a part of the latter will strike the heel 38 and will move the blade-carrier forward against the action of the spring 44 X , retracting the blades while closed into the housing 105 30, and causing them to be opened by engagement of the finger 36 with the front end of the slot 31, so that the parts will thereby be restored to the position shown in Fig. 13, and in full lines Fig. 14. 110

I have provided a detent instrumentality to normally retain the parting means in the position shown in Figs. 110 12 and 13, and also in Fig. 1, the detent in the present embodiment of my invention being withdrawn from operative position by or through the actuation of the replenishing mechanism.

The temple stand T^X has a rigid, laterally-extended pin 46 behind the shoulder or abutment 42, and upon the pin is slidably mounted a detent shown as a block 47, rigidly attached to one member as 48 of an adjustable link 48, 49, the overlapped ends of the two link members being adjustably connected by clamping bolts 120 50, Fig. 1.

The link member 49 extends to the right to a bell-crank 51, 52, mounted to swing in a substantially horizontal plane on an upright post 53 X , on the filling-feeder stand, a suitable spring 54 acting upon the bell-crank 125 to normally maintain it in the position shown in Figs. 1 and 2, with the detent 47 in co-operation with the shoulder or abutment 42 of the blade-carrier.

The bell-crank arm 52 is downturned at 53, adjacent to and in front of the depending extension f^3 of the transfer, so that when the latter is rocked to effect filling replenishment, the bell-crank will be turned in the 5 direction of the arrow 54, Fig. 1, to pull the link 48, 49 to the right, and thereby withdraw the detent 47 from engagement with the abutment 42. Such withdrawal of the detent instantly releases the blade-carrier, and the actuating spring 44 $\times$ thereof moves the latter from 10 normal to operative position, to first locate the blades as in dotted lines Fig. 14, in readiness to receive between them the old filling-end (which is that part of the filling extending from the cloth to the shuttle in the shuttle-box B), and thereafter to close the blades 15 upon and part such filling-end.

It will be understood that when the lay is fully forward, the engagement thereof with the heel 38 prevents the operation of the parting means until the backward swing or movement of the lay following replenishment, 20 but when the transferring mechanism and lay are in the position shown in Fig. 6, the detent 47 is withdrawn and the blades 33 and 34 would operate to part the filling adjacent the cloth.

By the two separate parting means above described, 25 the old filling-end is parted in two places, at the edge of the cloth and at the shuttle respectively, and after replenishment the shuttle is shot across the lay, and the fresh filling is laid while the new filling-end, leading from the hopper or filling-feeder to the nearer edge 30 of the cloth is left, and I have provided means which I will now explain whereby on the next forward beat of the lay, a second operation of the parting means adjacent the edge of the cloth will be effected to part the new filling-end. If nothing were provided to prevent it, the next forward beat of the lay after replenishment would cause the blade-carrier to be moved forward and the spring 54 would return the bell-crank and the adjustable link 48, 49 to normal position, to thereby return the detent 47 to operative position, and 35 there could not be two successive operations of the parting means. Herein, however, I retard the restoration of the parting means to normal or inoperative position, and during the retarded period, the lay acts to cause a second parting operation, to part the fresh filling-end.

An upturned and rearwardly extended finger 55 is 40 formed on the slotted plate 56 which rests upon the member 49 of the link and is clamped thereto by the bolts 50, the said finger being normally on the left of a retarding member 57, Figs. 1 and 12, and in the present embodiment of my invention, I have shown such retarding member as a prolongation of the upper end of the vibrating actuator or weft hammer W $\times$ of the filling-detector or fork w $\times$ at the right hand side of the loom.

The vibrator W $\times$ is at its extreme rear position, and is just about to move forward when the shuttle is picked across to the replenishing side of the loom, so that if the fork w $\times$ detects filling absence on that pick, the fork-tail will co-operate with the hook w, and a change in the 55 operation of the loom will be effected in well known manner.

When the vibrator is in its rearmost position, the retarding device 57 is beyond the rear end of the finger 55, so that the actuation of the replenishing mechanism

is free to withdraw the detent 47, and thereupon the finger 55 is moved to the right of the path of movement of the retarding device 57, viewing Fig. 1, and such retarding device will be moved forward into position to engage the finger, but on the opposite side thereof, before the return of the replenishing mechanism to normal position has released the bell-crank 51, 52. Consequently as the vibrator or weft-hammer W $\times$ moves forward, it will then wipe over the left hand face of the finger 55 and will prevent the return of the detent 47 to operative position for the time being.

The fresh filling having been shot across, the new filling-end is present between the cloth and the filling-feeder, and as the lay beats up, it engages the heel 38 of the blade-carrier, the parts then being in the position shown in Fig. 15, and the parting mechanism is restored to the condition shown in full lines Fig. 14, as the lay completes its forward movement. The fresh filling is thereby beaten in, and as the lay swings back the spring 44 $\times$ operates to project the blades 33, 34 in open position, see dotted lines Fig. 14, to receive between them the fresh filling-end, and as the lug 36 hits the rear end of the slot 31, the blades will be closed upon and will part such new or fresh filling-end. By this time, however, the vibrator W $\times$ has again assumed its rear-most position, releasing the finger 55 and the detent, 50 which latter by the action of the spring 54 will press against the side of the shoulder or abutment 42.

When on the next forward beat of the lay, the heel 38 is engaged, the blade-carrier and shoulder or abutment 42 will be moved forward, the latter beyond the detent, 55 so that the detent will snap into place in its operative position, as in Figs. 12 and 13, so that when the lay swings back the abutment will bring up against the detent and the parting mechanism is thereby retained in inoperative position with the blades retracted or housed, 60 until the next replenishment of filling is called for. When such parting mechanism is in normal position, the two heels 38 and 42 are so positioned with relation to each other as to be practically engaged simultaneously on the beat-up of the lay, so that the temple is moved forward and the parting means bodily therewith, the temple shank sliding in the stand T $\times$ in usual manner, but as the parting means move forward with the temple, the blades will remain retracted within the housing, 65 and hence cannot interfere with the filling when the shuttle is boxed at the replenishing side of the loom and the loom is running properly.

The adjustable connection between the two parts 48, 49 of the link and the blade 56 provides for adjustment of the throw of the detent, and for regulation of the retarding finger 55.

So far as the retarding device is concerned, it need not necessarily be a part of the weft hammer, as any vibrating member timed to vibrate properly will operate in the same manner, but in the case of a double fork loom, the weft hammer of the right hand fork affords at once a proper and very convenient retarding device to operate as has been described.

When the detent has been withdrawn to permit the spring 44 $\times$ to operate the parting means, the rearward movement of the blade-carrier 32 is limited by the engagement of the shoulder or abutment 42 with the pin 46 on the temple stand.

The upper end of the shuttle-feeler arm y^x is bifurcated to present at its upper end a rearwardly extended jaw 58 longitudinally grooved at 59 along its upper edge and a branch 60 parallel to the jaw but extending rearwardly to a less distance, as shown in Fig. 8. This branch has pivoted to it at 61 a jaw-carrier 62 provided with a downturned heel 63 and with an overhanging broad jaw 64, longitudinally grooved on its lower face at 65, and preferably provided with pads 66, see Fig. 10, 10 of leather or other suitable cushioning material.

When the jaws close, as shown in Fig. 10, the pads rest upon the upper face of the jaw 58 at each side of the groove 59 therein, and serve to firmly clamp or catch the filling at a point between the two parting means 15 hereinbefore described.

A side elevation of the jaws is shown in Figs. 8 and 9, in the former the jaws being closed, and in the latter the said jaws are open. The shuttle-feeler arm y^x moves rearwardly when filling-replenishment is called for, and 20 if the shuttle is properly boxed, the jaws 58 and 64 will move across the raceway of the lay close to the inner end of the shuttle, and filling-replenishment will follow, but if the shuttle is too far out of the box, the ends of the jaws will engage the side wall of the shuttle, and prevent 25 filling-replenishment in a manner common to looms of this type. A lateral pin 67 on the jaw-carrier 62 passes loosely through a slot 68 in the branch 60, see Fig. 8, the projecting end of the pin bearing against a spring 69, to hold the jaw 64 in open or in closed position 30 until positively removed therefrom. If the jaw is open, as will be the case when the shuttle-feeler device moves rearwardly, the lay on the beat-up thereof will hit the heel 63, and will turn the movable jaw on its pivot 61 from open position Fig. 9 to closed position 35 Fig. 8. Such closing of the jaws clamps or catches the filling between them, and the jaws remain closed as the feeler-arm y^x resumes its normal position, shown in Fig. 1, so that the cut out piece of filling is carried forward out of the way. The jaws are opened on the 40 movement of the arm y^x to operative position, and this is effected by a cam-like opening device 70 forming the outer end of a rib 71 on the free end of an arm 72 pivotally connected at 73 to a block 74 bolted to the breast-beam, see Figs. 1 and 7.

Referring to Figs. 7 and 11, the opening device is shown as substantially triangular and it is adapted to enter between the faces of the closed jaws and to travel through the grooves 59, 65, as the arm y^x swings rearwardly to thereby separate or open the jaws, the opening device passing out from between the jaws at the forward portion of the jaw 64, which latter on its upper face is convexed as at 75, Fig. 9. When the jaw 64 has passed forward beyond the opening device 70, the latter travels in the groove 59 as the shuttle-feeler reaches 50 its operative position, and after replenishment of filling, when the arm y^x swings back to normal position, the opening device 70 will ride up over the convex portion 75 of the jaw 64, over the top of such jaw, and will drop off the front end of the jaw into the position shown in 55 Fig. 7, and also in Fig. 1, in readiness to open the jaws on the next rearward movement of the shuttle-feeler device.

The jaws form a thread-catcher, and they are opened 60 positively as the thread-catcher is moved into operative position, to receive the filling-end, and said jaws

are positively closed upon such filling-end by or through the action of the lay on the forward beat, and the jaws remain closed after the shuttle-feeler has returned to normal position until filling-replenishment is again to be effected.

In the present embodiment of my invention, the rearward movement of the shuttle-feeler device is effected by means of a spring 76, Fig. 7 coiled around the rocker-shaft y , one end of the spring bearing against a part 77 of the arm y^x , and the other end of the spring 75 being held fast by a lug 78 on a bracket secured to the loom side. The particular means for operating the shuttle-feeler is not of importance, however, so far as my present invention is concerned, as the shuttle-feeler device can be moved into operative position in various ways.

It will be seen that the device which parts the filling between the cloth and the shuttle cannot act unless the replenishing mechanism operates to effect filling replenishment, nor can the thread-catching device on 85 the shuttle-feeler engage and hold the thread if filling replenishment is not effected, because if the feeler strikes the shuttle the thread-catcher remains open, as shown in Fig. 9.

Should it by any chance catch the thread at such 90 time the parting device could not operate, and the only result would be a loop of filling extending outside of the cloth. Consequently the so-called "Aumann stripe" cannot be made in the cloth. Such a stripe is caused by a feeler thread-cutter operating to cut the filling at a 95 time when the shuttle does not fully enter the replenishing shuttle-box, the engagement of the feeler with the shuttle preventing replenishment of filling. When this happens the shuttle is picked to the opposite side of the loom, the trailing filling catches on at that side and the weaving goes on as before, leaving a mis-pick nearly the entire width of the cloth, making the stripe referred to.

The mechanism herein described prevents the formation of such stripes, as will be manifest from the foregoing explanation.

My invention is not restricted to the precise construction and arrangement herein shown and described, as the same may be varied in many particulars by those skilled in the art without departing from the spirit and scope of my invention.

Having fully described my invention, what I claim as new and desire to secure by Letters Patent is:

1. In a loom, in combination, automatic filling-replenishing mechanism, a temple, means carried thereby to part the old filling-end between the cloth and the shuttle only by or through the operation of the replenishing mechanism and to thereafter part the new filling-end immediately after the new filling has been laid.

2. In a loom, in combination, automatic filling-replenishing mechanism, a lay, and means mounted independently of the lay and controlled positively and successively by the replenishing mechanism and the lay to first part the old filling-end adjacent the cloth upon filling replenishment and thereafter to part the new filling-end immediately after the new filling has been laid.

3. In a loom, in combination, a lay, automatic filling-replenishing mechanism, a temple, blades carried thereby to part the filling adjacent the cloth, a spring-actuated device to operate the blades, means to permit the operation of said device upon filling-replenishment, to part the old filling-end, and means to effect by or through the lay a second operation of the parting blades to part the new filling-end due to filling replenishment.

4. In a loom, in combination, a lay, automatic filling-replenishing mechanism, a temple, blades carried thereby to part the filling adjacent the cloth, spring-actuated means to operate the blades, a detent to normally prevent said means from operating, operative connections between the detent and replenishing mechanism to withdraw the former upon operation of the latter, whereby the spring-actuated means cause the blades to coöperate with and part the old filling-end, a retarding device to engage the 10 detent when withdrawn and maintain it withdrawn for a predetermined period, and means to cause a second operation of the blades by or through the lay during such period and after filling replenishment, to part the new filling-end due to such replenishment. 80
15. 5. In a loom, in combination, a lay, automatic filling-replenishing mechanism, a temple, pivotally connected blades carried thereby and bodily movable into and out of operative position, spring-actuated means to move the blades into operative position and to effect closure thereof, 85 20 a member connected with said blades and adapted to be at times engaged by the lay, to retract the blades and effect opening thereof, a detent to normally retain the blades retracted in inoperative position, connections between the detent and replenishing mechanism to withdraw 25 the former upon operation of the latter, whereby the spring-actuated means cause the blades to coöperate with and part the old filling-end, and a retarding device to maintain the detent withdrawn for a predetermined period, the lay during such period acting upon the member connected 30 with the blades to retract them, the spring-actuated means causing a second operation of the blades as the lay moves back to part the new filling-end due to filling-replenishment, the retarding device releasing the detent thereafter and permitting it to act after a second engagement of the 35 lay with the member connected with the blades. 90
6. In a loom provided with automatic filling-replenishing mechanism, in combination, means, the actuation of which is effected by the operation of said mechanism, to part the filling adjacent the cloth, separate means to part the old filling-end within the shuttle, a shuttle-feeler movable into operative position when the shuttle is properly boxed for filling replenishment, and means carried by said feeler to engage and remove the piece of filling parted by the parting means. 95
40. 7. In a loom provided with automatic filling-replenishing mechanism, in combination, means to positively part the filling adjacent the cloth upon filling replenishment, separate means to enter the shuttle and part the old filling-end, and devices to effect the operation of the said separate 100 means only by or through actuation of the replenishing mechanism. 105
50. 8. In a loom provided with automatic filling-replenishing mechanism, a lay, means to enter the shuttle at the replenishing side of the loom and part the old filling and 110 connections between the replenishing mechanism and the parting means, to operatively position the latter when filling is to be replenished, the actuation of the parting means being effected at such time by the lay. 115
55. 9. In a loom, in combination, automatic filling-replenishing mechanism, means the operation whereof is effected by or through the actuation of said mechanism to part the old filling-end on the pick on which filling is replenished, and separate, positively operated means to enter the shuttle and part such filling-end only upon filling-replenishment. 120
60. 10. In a loom, in combination, automatic filling-replenishing mechanism, positively acting means to part the old filling-end adjacent the cloth on the pick on which filling is replenished and to part the new filling-end immediately 125 after the pick following replenishment, and separate means rendered operative by actuation of the replenishing mechanism to enter the shuttle and part the old filling-end thereat only upon filling replenishment. 130
70. 11. In a loom, in combination, automatic filling-replenishing mechanism, a lay, means controlled successively by the said mechanism and the lay to part the old filling-end adjacent the cloth and thereafter to part the new filling-end due to filling replenishment immediately 135 after the new filling has been laid, and separate means 140 to operatively position by the replenishing mechanism 80 and actuated by the lay to part the old filling-end at the shuttle. 145
12. In a loom, in combination, a lay, automatic filling-replenishing mechanism, including a rocking transfferer, a blade-carrier adapted to swing about a fixed fulcrum, 85 relatively movable blades mounted on the carrier, to part the old filling-end adjacent the shuttle upon filling replenishment, a blade-closing device operated by engagement with the lay when the blade-carrier is operatively positioned, and connections between the transfferer and 90 blade-carrier to swing the latter into and out of operative position by movement of the transfferer. 95
13. In a loom, in combination, a lay, automatic filling-replenishing mechanism, including a transfferer, a movable blade-carrier, parting blades mounted thereon and 100 adapted to part the old filling-end adjacent the shuttle, a device to open the blades, a blade-closing device, said closing device being engaged by the lay to close the blades when the blade-carrier is operatively positioned, and means to move the blade-carrier into operative position by operative movement of the transfferer and to retract the blade-carrier by movement of the transfferer when it returns to normal position. 105
14. In a loom, in combination, a lay, automatic filling-replenishing mechanism, including a transfferer, a movable blade-carrier, parting blades mounted thereon and 110 adapted to part the old filling-end adjacent the shuttle, means to close the blades by or through engagement with the lay when the blade-carrier is operatively positioned, a yielding connection between the blade-carrier and transfferer to operatively position the former when the latter operates, and separate means to positively restore the blade-carrier to inoperative position by or through retractive movement of the transfferer following filling replenishment. 115
15. In a loom, in combination, a lay, automatic filling-replenishing mechanism, including a rocking transfferer, a blade-carrier, adapted to swing about a fixed fulcrum adjacent the transfferer path and having a fixed blade at its lower end, a movable blade pivoted on the blade-carrier and coöoperating with the fixed blade and having an attached arm adapted to be at times engaged by the lay to close the blades, operating connections between the blade-carrier and transfferer, to operatively position the former by transferring movement of the latter, whereby the blades will coöperate with and part the old filling-end at the shuttle, and to return the blade-carrier to inoperative position by retraction of the transfferer, and a blade-opening device to act upon the arm of the pivoted blade when the blade-carrier is returned to normal position. 120
16. In a loom, in combination, automatic filling-replenishing mechanism, a movable blade-carrier provided with relatively-movable blades to part the old filling-end at the shuttle, connections between the blade-carrier and replenishing mechanism, to move the former into operative position by or through complete actuation only of the latter, a lay, and means governed thereby to effect closing movement of the blades when the blade-carrier is operatively positioned, and separate connections between the blade-carrier and replenishing mechanism to return the former to normal, inoperative position immediately after filling replenishment. 125
17. In a loom in combination, automatic filling-replenishing mechanism, a lay, a shuttle-box thereon at the replenishing side of the loom having an opening in its front wall, a shuttle adapted to contain a supply of filling and having an opening adapted to register with the opening in the shuttle-box wall when the shuttle is properly boxed, and automatically operated parting blades adapted to enter said openings when filling is replenished, to part the old filling-end at the opening in the shuttle. 135
18. In a loom, in combination, automatic filling-replenishing mechanism, a lay, a shuttle-box thereon at the replenishing side of the loom having an opening in its front wall, a shuttle adapted to contain a supply of filling and having an opening adapted to register with the opening in the shuttle-box wall when the shuttle is properly 140

boxed, automatically operated parting blades adapted to enter said openings when filling is replenished, to part the old filling-end at the opening in the shuttle, and means controlled by the replenishing mechanism to part the old

5 filling-end adjacent the cloth.

19. In a loom provided with automatic filling-replenishing mechanism, in combination, a temple, means carried thereby to part the filling adjacent the cloth, an instrumentality to effect the operation of said means only

10 when filling replenishment is effected, a shuttle-feeler to

permit filling replenishment only when the shuttle is properly boxed, and means carried by the said feeler to engage and retract the piece of filling when parted by the parting means.

In testimony whereof, I have signed my name to this 15 specification, in the presence of two subscribing witnesses.

JONAS NORTHRUP.
